UNITED STATES PATENT OFFICE.

CLINTON C. HUTCHINSON, OF PORTLAND, OREGON.

EXCAVATING, DITCHING, AND GRADING MACHINE.

No. 834,729.

Specification of Letters Patent.

Patented Oct. 30, 1906.

Application filed September 7, 1905. Serial No. 277,834.

To all whom it may concern:

Be it known that I, CLINTON C. HUTCHINSON, of Portland, in the county of Multnomah, and in the State of Oregon, have invented a certain new and useful Improvement in Excavating, Ditching, and Grading Machines; and I do hereby declare that the following is a full, clear, and exact description thereof, reference being had to the accompanying drawings, in which—

Figure 1 is a plan view of a machine constructed in accordance with my invention, the floor being removed. Fig. 2 is a side elevation with the nearer supporting and driving wheels removed, the axles thereof being in section. Fig. 3 is a rear elevation of said machine. Fig. 4 is a detail view in section on the line A' A' of Fig. 1. Fig. 5 is a transverse section in detail on the line D D of Fig. 3, with some of the parts shown in elevation. Fig. 6 is a detail view, in side elevation, of a portion of the mechanism for raising and lowering the front end of the excavator, and Fig. 7 is a top plan view of the same.

My invention relates to excavating, ditching, and grading machines, and has among its objects the provision of a machine of this description which will enable the discharge of the excavated material on the same side of the canal or ditch when the machine is traveling in either direction, which will enable deeper working of the excavator in relation to the wheel-level than is possible with prior machines with which I am familiar; which can be operated in soils of various sorts, including very light material and material including boulders, which will form trenches or ditches with vertical side walls, and which may be operated with greater speed of travel and require less power for operating it in proportion to the material handled than machines heretofore produced; and for the attainment of these and other objects and advantages my invention consists in the machine having the construction substantially as hereinafter specified and claimed.

In the machine which I have selected to illustrate an embodiment of my invention there is a frame composed of longitudinally-extending beams 1 and cross-beams and braces forming a light but strong structure and mounted upon a rear axle 93, on which are journaled supporting and drive wheels 2, and a front axle on which are journaled sup-

porting-wheels 3. In the space between the front and rear axles and preferably nearer the former is situated the excavator A, consisting of a double share or cutter and mold-board of one or more parts, having a centrally-located point with a laterally and rearwardly inclined forward cutting edge and an upper surface so inclined upward and rearward as to readily pass through the soil or material and lift the same without causing it to be moved laterally, and to prevent the material dug up passing sidewise from the excavator there is on each side thereof a side plate 4^a.

The excavator A is attached by two standards 4^c and 5, at both sides thereof, to a pair of longitudinally-extending beams 4^b, which form a frame or support by which the excavator is rigidly supported, and said frame or support is movably supported from the machine-frame so that the excavator may be raised and lowered and adjusted at the desired working angle. For this purpose there are pivoted to the front ends of the beams 4^b a forwardly-extending stirrup 7, whose front end is pivotally connected to the lower end of a lever 8, pivoted at its upper end to a U-bolt 9, fastened to the front-axle bolster, and there are pivoted to the rear ends of said beams 4^b rearwardly and upwardly inclined bars 27, which at their rear ends are respectively pivoted to the two side beams 1 of the machine-frame. The bars 27 may be attached to the beams 4^b at points farther forward than shown, and, if desired, additional bars may be employed.

To the lever 8 is attached a clevis 10 for the attachment of draft-animals or other power for moving the machine forward, it being observed that there is thus a direct connection of the power with the excavator as well as the remainder of the machine. Besides the excavator A the beams 4^b support near their front ends a tread-wheel 6, journaled in a bracket pivoted to said beams, so that it may be adjusted up or down for different depths of cut, and cutters 95, situated just in advance of the excavator A in such position as to engage and turn any rocks or boulders that may be encountered in operating in soil or material containing them and push or roll them aside, if of a large size, and prevent their passing to the conveyors.

To the front end of the frame formed by the beams 4^b there is attached a chain or

cable 11, that thence extends upward and over a sheave 12 and from the latter extends rearward over a sheave 14 and thence upward to a drum or windlass 21, having a hand-wheel 23, by which it may be revolved, a pawl and ratchet-wheel 22 being, as usual, provided for the drum or windlass. From the rear end of each of the beams 4^b a chain or cable 23 runs to the drum or windlass 21.

10 It will be seen that by means of the drum or windlass the excavator may be raised or lowered, as the sheave 14, over which the chain or cable 11 passes, is vertically movable, and for this reason it is journaled in a bearing-block 15, having a vertical threaded opening through which the threaded portion of a vertical shaft 17^a passes, so that by the revolution of said shaft (which is provided at its upper end with a crank or hand wheel 20, by which it may be revolved) the bearing-block 15 may be raised or lowered, and thus the sheave 14 raised or lowered, and thereby the angle at which the excavator works adjusted. The drum or windlass 21 is journaled in bearings 24, supported by uprights or posts 25, rising from a cross-piece 17 of the machine-frame. At its upper end the screw-shaft 17^a is journaled in a bearing 18^a, supported by the posts 25, and at its lower end 30 it has a bearing in a projection 19 on a block 16, which has guides for the slide-block 15 and which is attached to and supported by the frame cross-piece 17. Collars 18, respectively above and below the lower shaft-bearing 19, pinned or otherwise fastened to the shaft 17^a, restrain the latter from longitudinal movement when it is revolved for the purpose of raising or lowering the sheave-carrying block 15.

40 Material lifted by and passing over the excavator A is delivered at the rear end of the latter to an elevator B, that consists of an endless apron or conveyer 34, passing over a roller 37, situated a short distance in advance of the rear end of the excavator, but below the upper side of the same, and passing over a roller 33, said rollers 33 and 37 being journaled in bearings in and supported by a frame comprising two side bars 36, that 50 from the roller 37 incline rearwardly and upwardly, so that the upper side of the apron travels from the mold-board rearwardly and upwardly. As the elevator B passes beneath the rear axle 93 the latter is arched where it 55 crosses the elevator to allow the latter to be carried upward at its rear end to the required height. The roller 33 is carried by a shaft 31, the ends of which project beyond the ends of the roller and have bearings in 60 brackets 29, fastened to the machine-frame, and at the lower forward ends of the side bars 36 the latter are loosely attached to the excavator sides 4^a by a horizontal rod 38, whose ends are seated in elongated holes or 65 openings in said side plates 4^a. It will

therefore be seen that the elevator B is shiftable with the excavator A, so that at all times these two will be in proper working relation for the delivery of material from the excavator A to the apron of the elevator. 70 Preferably to support the upper portion of the apron 34 a number of rollers 35 are journaled in the side plates 36 at suitable distances apart between the rollers 33 and 37, and to prevent material being carried up by 75 the apron 34 spilling from the sides thereof there is at each side of the latter a side plate 39.

Power to drive the apron of the lifter B is taken from the drive-wheels 2 in a well-known manner, each drive-wheel being provided with a gear 65, with which meshes a pinion 66 on a transverse shaft 67, journaled in bearings 68 on the frame-beams 1, upon which shaft 67 is a band or sprocket wheel 69, from which a belt or sprocket-chain 70 80 runs to a sprocket-wheel 32 on the shaft 31. The pinions 66 are provided, as usual, with ratchet mechanism for connecting them to the shaft 67.

By means of the elevator B the excavated material is carried rearward in line with the direction of the ditch or trench being dug, and it is therefore necessary to provide means for carrying such material to one side of the ditch, and for this purpose I provide a conveyer C, which receives material from the elevator B and carries it laterally to the desired position at one side of the ditch or trench. The conveyer C is similar in construction generally to the elevator B, it 90 comprising an endless apron or carrier 60, which from a point beneath and slightly forward of the rear end of the elevator B passes over a roller 55 and thence extends outward and laterally and preferably upward to a 100 roller 61, said rollers being journaled in bearings in parallel side bars 53. The side bars 53 of the conveyer C near their inner ends are pivotally mounted on the hubs or bearing-pieces 52 on the arms of a horizontally 110 rotatable or swinging yoke or open frame 51, so that the conveyer C may be raised or lowered at its delivery end by vertical movement on said hubs and swung horizontally on the yoke or frame 51 to place its delivery end 115 at either side of the machine, so that as may be desired the material may be deposited upon the same side of the ditch or trench irrespective of the direction of travel of the machine, which under some conditions is 120 very desirable—as, for example, when a trench or canal is being excavated alongside of a hill.

It will be seen that by employment of the yoke or open frame 51 a support for the carrier C is possible above it, and this enables the provision of a support of ample strength to sustain the heavy side thrust of the carrier and enables the inner end of the carrier to be situated quite low down, a low position as 130

possible of the inner end of the carrier C being desirable, because it avoids undue lengthening of the elevator B and the machine. The inner end of the carrier C is projected to at least a point where it alines with the side of the elevator B, and it is thereby assured that all material coming from the elevator B will be received by the carrier C, and as a portion of the carrier C at the receiving end thereof will at all times be in position to receive all material coming from the elevator B, even when shifting the carrier C from one side of the machine to the other, it is possible, if it should be desired, to shift the carrier C to place its delivery end from one side of the machine to the other while the machine is working.

For raising and lowering the carrier C there is pivotally attached to the side plates 20 53 a stirrup 80, to which is attached a sheave 81, from which a chain or cable 85 passes over a sheave 84 and thence through a block 82, in which the sheave 84 is journaled, and which block is supported from the frame of 25 the machine by a light framework composed of bars 83, and from the block 82 it passes to a drum or windlass 87, supported on posts or uprights 88, rising from the machine-frame, which windlass is provided with a hand-wheel 90 and pawl and ratchet 89. One end of the chain or cable 85 is fastened to the block 82. There are two sheaves 84 on opposite sides of that portion of the chain or cable which passes through the block 82 to 30 the drum or windlass, so that whether the carrier C be swung to one side of the machine or the other there will be a sheave 84 for the chain or cable to work over.

The yoke or frame 51, which constitutes 40 the pivotal support on which the carrier C may be revolved through one hundred and eighty degrees to transfer its delivery end from one side of the machine to the other, is journaled at its upper end in a vertical bearing 46 at the rear end of a horizontal beam or bar 45, which is bolted to and extends rearwardly at the transverse center of the machine from a cross-bar or beam 42, mounted upon the blocks 41 upon the two side beams 45 45 1 of the machine-frame, and said bar or beam 45 is also attached to and supported by a transverse bar or beam 44, which at its ends is supported from the side beams 1 by blocks 43. At its lower end the yoke or frame 51 is 50 pivoted in a bearing 49 at the rear end of a horizontal bracket 48, which is bolted to and extends rearwardly from an upright or post 47, extending downward from each side frame 1, each post 47 being suitably braced by a 55 bar or brace 29, that extends therefrom to the rear axle 93. The framework described for pivotally supporting the yoke or frame 51 with the carrier C is a light but strong one.

Passing through and having bearings in 60 the arm-hubs 52 is a shaft 57, which is used

as the means for transmitting power to the apron 56 to move the latter, and for this purpose it is provided on each end with a bevel-gear 58, which gears are adapted to mesh, respectively, with two gears 77 on a transverse shaft 76, according as the carrier C is in position at one side of the machine or the other, the gears 77 being on opposite sides of a plane passing rearward through the axis of the yoke or frame 51. Motion is imparted 75 to the shaft 76 by a sprocket or band wheel 75 thereon, which is connected by a band or chain 74 with a sprocket or band wheel 73 on the shaft 67. On the shaft 57 is a band or sprocket wheel 59, from which a belt or chain 80 60 runs to a sprocket or band wheel 61 on the shaft of the roller at the discharge end of the carrier C.

For firmly holding the carrier C in position at one side of the machine or the other an eye 85 or socket 96 is provided on each side beam 1, and an eye or socket 96^a is provided on each side bar 53 of the carrier near the outer end thereof, and a rod or bar 97, whose opposite ends are bent at right angles, is inserted at 90 one end in the appropriate socket 96 and at the other end in the appropriate socket 96^a.

The conveyer C, like the elevator B, has side pieces 63 to prevent spilling of the material over the sides of the apron 56 and at 95 its receiving end a cross-piece 63^a for a similar purpose, and rollers 55 are provided at intervals between the end rollers of the apron and, if desired, the conveyer C may be 100 made in sections.

Reinforcing-blocks 54 are applied to the side pieces 53 of the conveyer C where the bearings for the shaft 57 are situated, and in particulars which it is not thought necessary to mention the machine-framework is braced 105 or stiffened, it being understood, of course, that such details of construction as these do not relate to the principle of the invention, but are matters which may be employed or not or varied according to the necessities of 110 the structure of the machine and the work it is designed to do.

It is thought the operation of my machine will be readily understood from what has already been said, so that only a brief description of its operation is now necessary. The excavator A is lowered to the position for making the desired depth of cut by operating the drum or windlass 21 by means of the hand-wheel 23, and the inclination of the excavator is adjusted to the desired angle by revolving the screw-shaft 17^a to move the sheave 14 vertically to cause it to act upon the chain or cable 11. The machine being drawn forward, the soil or material will be 115 lifted by the excavator A and delivered therefrom to the apron of the elevator B and by the latter be carried backward and upward and discharged upon the apron of the carrier C, by means of which it will be passed 120 125 130

laterally and finally discharged at a point on one side of the ditch or canal being excavated, the outer or discharge end of said carrier C being adjusted to such height as may be necessary or desirable by means of the windlass 87, operated through the medium of the hand-wheel 90. Should the travel of the machine be reversed and it be desired to deliver the material upon the same side of the ditch, this can be done by swinging the carrier C on the yoke or frame 51 to place its delivery end upon the opposite side of the machine.

By the employment of the elevator B and the carrier C, so that the newly-excavated material may be carried backward and upward and thence to one side of the ditch or canal I am enabled to cut a ditch or canal with vertical side walls which of course cannot be done where the excavator must itself turn the newly-excavated material sidewise or laterally, and as by my construction a comparatively slight angle may be given the excavator and the elevator B a cut of considerable depth can be made, the friction of the material on the excavator is reduced, an increase of speed of the machine is possible, and such light material as lava soil may be successfully worked in.

Having thus described my invention, what I claim is—

1. In an excavating-machine, the combination of an excavator, and a conveyer for the discharge of excavated material that extends laterally and is shiftable to place its outer or discharge end at either side of the machine, operated by power applied at the discharge end.

2. In an excavating-machine, the combination of an excavator, a conveyer for the discharge of excavated material, consisting of an endless apron that extends laterally and upward, and is shiftable to place its outer or discharge end at either side of the machine, and means for imparting motion to said conveyer, acting thereon at its outer end.

3. In an excavating-machine, the combination of an excavator, a conveyer for the discharge of excavated material, consisting of an apron and rotatable supports for the apron, said conveyer extending laterally to deliver material at the side of the machine, and one of said rotatable supports being situated at the outer or discharge end, means for applying power to said rotating support at the outer or discharge end of the conveyer, to impart motion to the apron, and a support for the conveyer that permits the shifting of the position thereof to place its discharge end at either side of the machine.

4. In an excavating-machine, the combination of an excavator, a horizontally-movable conveyer for excavated material, consisting of an endless apron and rotatable supports therefor, one of which is at the outer

end of the conveyer, and means for driving the apron acting on said rotatable support at the outer end of the conveyer.

5. In an excavating-machine, the combination of an excavator, a conveyer for the discharge of excavated material, shiftable to place its delivery end at either side of the machine, and a bearing or supporting means which permits such shifting situated above the conveyer.

6. In an excavating-machine, the combination of an excavator, a conveyer for the discharge of excavated material, shiftable to place its delivery end at either side of the machine, and a pivotal support for said conveyer at the inner or receiving end thereof, and situated above the conveyer.

7. In an excavating-machine, the combination of an excavator, a material-carrier receiving material from the excavator, and carrying it longitudinally of the machine, and a conveyer extending transversely of the machine receiving material from the material-carrier, said conveyer being shiftable to place its discharge end at either side of the machine, and being extended at its receiving end so that at all times during its movement from one side of the machine to the other it receives all the material coming from the carrier.

8. In an excavating-machine, the combination of an excavator, a conveyer, a pivot for said conveyer whose axis is vertical, and bearings for said pivot, both above and below the conveyer.

9. In an excavating-machine, the combination of an excavator, a conveyer comprising a movable member, a pivoted support for said conveyer having a vertical axis upon which the conveyer may be shifted to place its delivery end at opposite sides of the machine, bearings for said pivoted support both above and below the conveyer, and gearing for driving the movable member in either of its positions at opposite sides of the machine.

10. In an excavating-machine, the combination of an excavator, a conveyer, a driving mechanism therefor including a shaft, bearings for the shaft, and a pivotal support for the conveyer, comprising frame-bars pivoted on the shaft-bearings.

11. In an excavating-machine, the combination of an excavator, a conveyer, a vertically-pivoted frame for the conveyer, driving mechanism for the conveyer, comprising a horizontal shaft journaled in arms of said frame, and conveyer-frame bars pivoted to hubs on said arms.

12. In an excavating-machine, the combination of an excavator, a suitable frame, a horizontally-movable conveyer, and a brace rod or bar extending between said frame and the conveyer.

13. In an excavating-machine, the combination of an excavator, a suitable frame, a

horizontally-movable conveyer shiftable to opposite sides of the machine, and a brace rod or bar to extend from the frame to the conveyer, adapted to be connected to said frame and said conveyer at both sides of the machine.

14. In an excavating-machine, the combination of an excavator, a material-carrier pivotally connected to and receiving material from the excavator and carrying it longitudinally of the machine, the pivoted connection being in a slotted bearing and a conveyer extending transversely of the machine receiving material from the material-carrier.

15. In an excavating-machine, the combination of an excavator, a material-carrier pivotally connected to and receiving material from the excavator and carrying it longitudinally of the machine the pivoted connection being in a slotted bearing, a second carrier receiving material from said first-mentioned carrier, and shiftable horizontally to change the position of its delivery end.

16. In an excavating-machine, the combination of an excavator, a material-carrier receiving material from the excavator and carrying it longitudinally of the machine, and a flexible connection between the excavator and said carrier comprising a pivot mounted in an elongated bearing-slot.

17. In an excavating-machine, the combination of an excavator, supporting means therefor which permit its angle to be adjusted, and a material-conveyer that is flexibly connected with and receives material from the excavator, whose receiving end is movable with the excavator said flexible connection consisting of a rod on one part and a slotted bearing therefor on the other part.

18. In an excavating-machine, the combination of an excavator, means for changing the angle thereof, a material-carrier, and a flexible connection between the receiving end of the latter and the excavator said flexible connection consisting of a rod on one part and a slotted bearing therefor on the other part.

19. In an excavating-machine, the combination of an excavator, and a material-carrier that is slidably and pivotally connected with the excavator that receives material from the excavator.

20. In an excavating-machine, the combination of an excavator, a material-carrier that receives material from the excavator, and a loose connection between the excava-

tor and said carrier permitting longitudinal movement of one relative to the other.

21. In an excavating-machine, the combination of a suitable frame, an excavator movably supported therefrom, a material-carrier extending rearwardly from the excavator, a loose connection between the excavator and said carrier, that permits longitudinal movement of one relative to the other and a pivotal support for said carrier on the frame.

22. In an excavating-machine, the combination of a frame, an excavator, and links pivotally connecting the excavator with said frame at the front and rear ends of the excavator.

23. In an excavating-machine, the combination of a frame, an excavator having a frame or support, links at the forward part of said support pivotally connecting it to the first-mentioned frame, and links at the rear of said support pivotally connecting it to said first-mentioned frame.

24. In an excavating-machine, the combination of a frame, an excavator movably supported therefrom, means for raising and lowering the excavator, including a cable or chain and a shiftable sheave, and means for shifting the position of said sheave.

25. In an excavating-machine, the combination of an excavator, and boulder-engaging devices in front thereof.

26. In an excavating-machine, the combination of a wheel-supported frame, an excavator, a draft-clevis, connections between said clevis and said frame, and connections between said clevis and the excavator.

27. In an excavating-machine, the combination of an excavator, a material-conveyer shiftable horizontally to different positions, a rope or chain for raising and lowering said conveyer, and two pulleys or guides for operating with the rope or chain in the different positions of said conveyer.

28. In an excavating-machine, the combination of a movably-supported excavator, a chain or rope for moving the same, a pulley or guide for the chain or rope, and means for moving said pulley or guide to change the angle of the excavator.

In testimony that I claim the foregoing I have hereunto set my hand.

CLINTON C. HUTCHINSON.
